UNITED STATES PATENT OFFICE.

CHARLES F. STEWART AND ERNEST N. DICKERSON, OF KINSTON, NORTH CAROLINA.

CLAMPING DEVICE FOR HEADING-MACHINES.

1,297,927.

Specification of Letters Patent. Patented Mar. 18, 1919.

Application filed February 12, 1918. Serial No. 216,810.

To all whom it may concern:

Be it known that we, CHARLES F. STEWART and ERNEST N. DICKERSON, citizens of the United States, residing at Kinston, in the 5 county of Lenoir and State of North Carolina, have invented certain new and useful Improvements in Clamping Devices for Heading-Machines; and we do hereby declare the following to be a full, clear, and 10 exact description of the invention, such as will enable others skilled in the art to which it appertains to make and use the same, reference being had to the accompanying drawings, and to the letters and figures of reference marked thereon, which form a part of 15 this specification.

This invention relates to new and useful improvements in machines for making heads for tobacco hogsheads, and the object 20 in view is to produce a simple and efficient apparatus of this nature whereby the entire head may be cut in one operation, and comprises a simple and efficient device of this 25 nature having various details of construction, combinations and arrangements of parts which will be hereinafter fully described, shown in the accompanying drawings and then specifically defined in the appended claim.

30 We illustrate our invention in the accompanying drawings which, with the letters of reference marked thereon, form a part of this specification and in which:

Figure 1 is a side elevation of our invention.

Fig. 2 is a view taken at right angles to the view in Fig. 1.

Fig. 3 is a top plan view, and

Fig. 4 is a vertical sectional view on line 40 4—4 of Fig. 3.

Reference now being had to the details of the drawings by letter—

A designates the frame of the apparatus and B designate bearing members which are 45 fastened to the frame in any suitable manner and in which the cylindrical ends D of the frame D' are journaled. A circular outlined table N has a plate N' secured to its under surface and is provided with a boss O 50 mounted in suitable bearings in the frame and upon which table the material out of which the head is made is placed preparatory to being cut. A clamping device consisting of two parallel beams or plates J are 55 fastened together by means of bolts J', and

L is a shaft which is fastened to said beams or plates, and R is a hollow shaft telescoping the shaft L and which is fastened to a suspending beam Q. The hollow shaft is provided with an elongated slot and S is an angled lever passing through said slot and pivotally mounted upon the pin S' and is adjustably held in one or another of the perforations in the shaft L. Clamping members T and T' are secured to the circumference of said hollow shaft R and to the member T a notched bar W is secured. A pin M is fastened to the lever S and is adapted to engage one or another of the notches in the bar W and one end of the lever S is connected to the clamping member T' through the medium of the link S².

In operation, the material out of which the heads are to be made is placed upon the table which, for convenience, may be tilted 75 at an angle, as shown in dotted lines in the drawings, and by pushing down the angled lever the clamping beams or plates may be forced down against the boards to hold the same securely upon the table and after 80 which by turning the table around against the saw the entire head may be cut and by which apparatus uniform heads may be made. By the provision of the machine made in accordance with our invention, it 85 will be noted that the same may be driven by power from above or below, as the table will not interfere with the pulley on the end of the saw mandrel. By the arrangement shown it will be noted that the saw is placed 90 near the center of the frame eliminating danger of the operator being cut by the saw. By the universal jointed connections shown the frame will permit the table to be tilted 95 at the desired angle for the material to be positioned when being sawed. By the provision of the table being mounted on a ball bearing spindle and working on roller-bearings, the same will be caused to be moved smoothly and easily at all times and eliminating any sudden strain upon the saw and also avoid any danger of belt flying off the saw incident to choking the same down.

What we claim to be new is:

A machine for cutting the entire head of 105 a hogshead, comprising a rocking frame and support therefor, a table pivotally mounted upon said rocking frame, a depending tubular shell having oppositely disposed slots therein, a shaft telescoping within said shell, 110

beams secured to the lower end of said shaft and spaced apart, a collar fixed to the shell, an angle lever passing through said slots, and a link pivotally connecting one 5 end of the lever with said collar, a link connecting the upper end of the shaft to the portion of the lever within the shell, a laterally extending bar secured to said shell and having notches in the under edge thereof,

and a pin secured to the lever engaging said 10 notches.

In testimony whereof we hereunto affix our signatures in presence of two witnesses.

CHAS. F. STEWART.
ERNEST N. DICKERSON.

Witnesses:

J. S. SPENCER,
A. W. WOOTEN.
